UNITED STATES PATENT OFFICE

127,532

DESIGN FOR A DRIVE-IN SERVICE BUILDING

Claude S. Eaton, North Hollywood, Calif.

Application February 8, 1941, Serial No. 98,848

Term of patent 3½ years

To all whom it may concern:

Be it known that I, Claude S. Eaton, a citizen of the United States of America, residing at North Hollywood, in the county of Los Angeles, State of California, have invented a new, original, and ornamental Design for a Drive-In Service Building, of which the following is a specification, reference being had to the accompanying drawings, forming a part thereof.

In the drawings:

Figure 1 is a plan view of the drive-in service building showing my design.

Figure 2 is a front elevation thereof.

Figure 3 is a plan view of the service building with the canopy removed.

Figure 4 is a side elevational view of the drive-in service building showing my design, the view being taken from the left of the structure as seen in the front elevation or Figure 1.

I claim:

The ornamental design for a drive-in service building, as shown.

CLAUDE S. EATON.
